UNITED STATES PATENT OFFICE.

WILLIAM J. KERR, OF WARREN, OHIO.

DESIGN FOR A SIGN.

Application filed August 20, 1924. Serial No. 10,500. Term of patent 14 years.

To all whom it may concern:

Be it known that I, WILLIAM J. KERR, a citizen of the United States, residing at Warren, in the county of Trumbull and State of Ohio, have invented a new, original, and ornamental Design for a Sign, of which the following is a specification, reference being had to the accompanying drawing, forming part thereof.

The figure is a front view of a sign, showing my new design in which the rotary wheel (shown in dotted lines), the ornamental border and the overhanging coping stand out in front in relief.

I claim:

The ornamental design for a sign, as shown and described.

WILLIAM J. KERR.
